(57) **CLAIM**

I claim the ornamental design for a grill for microwave oven,
as shown and described.

DESCRIPTION

FIG. 1 is an exploded perspective view of the grill for microwave oven consisting of two separable identical grill plate assemblies and two separable identical elastic retainers. The non-shown lower side of the upper grill plate assembly is identical to the shown upper side of the lower grill plate assembly and the non-shown lower side of the lower elastic retainer is identical to the shown upper side of the elastic retainer.

FIG. 2 is a perspective view of the grill for microwave oven in a position previous to use.

FIG. 3 is a perspective view of the grill for microwave oven in a working position.

FIG. 4 is a top view of the grill for microwave oven in the position previous to use.

FIG. 5 is a bottom view of the grill for microwave oven in the position previous to use.

FIG. 6 is a front elevation view (symmetrical to the rear elevation view) of the grill for microwave oven in the position previous to use.

FIG. 7 is a right elevation view (symmetrical to the left elevation view) of the grill for microwave oven in the position previous to use.

FIG. 8 is a top view of the grill for microwave oven in the working position.

FIG. 9 is a bottom view of the grill for microwave oven in the working position.

FIG. 10 is a front elevation view (symmetrical to the rear elevation view) of the grill for microwave oven in the working position; and,

FIG. 11 is a right elevation view (symmetrical to the left elevation view) of the grill for microwave oven in the working position.

The broken lines shown in the drawings are for illustrative purposes only and form no part of the claimed design.

1 Claim, 11 Drawing Sheets
